CLAIM

The ornamental design for a vision shield for a student
typist or the like, substantially as shown and described.

DESCRIPTION

FIG. 1 is a front elevational view of a vision shield for
a student typist or the like showing my new design;

FIG. 2 is a rear perspective view thereof;

FIG. 3 is a top plan view of FIG. 1;

FIG. 4 is a bottom plan view thereof; and

FIG. 5 is a right side elevational view thereof.
